UNITED STATES PATENT OFFICE

106,536

DESIGN FOR A HANDWRITING GUIDE FOR PENCILS OR LIKE ARTICLES

Carmon C. Heim, Oakland, Calif.

Application March 25, 1937, Serial No. 68,403

Term of patent 14 years

To all whom it may concern:

Be it known that I, Carmon C. Heim, a citizen of the United States and resident of the city of Oakland in the county of Alameda and State of California, have invented a new, original, and ornamental Design for a Handwriting Guide for Pencils or Like Articles, of which the following is a specification, reference being had to the accompanying drawing, forming part thereof.

The essential feature of my design for a handwriting guide for pencils or like articles consists in a configuration including a generally upwardly convex member with a concave bottom and rounded legs and with an upstanding member at one side, the latter terminating in a loop.

In the drawing:

Figure 1 is a perspective view of a guide embodying this invention.

Figure 2 is a side elevation view of the guide of Figure 1.

The important features of my design are shown in full lines, the pencil shown in broken lines is for the purposes of clarity.

I claim:

The ornamental design for a handwriting guide for pencils or like articles, substantially as shown and described.

CARMON C. HEIM.
